United States Patent Office

Des. 188,567
Patented Aug. 9, 1960

188,567

MOTION PICTURE CAMERA

Raymond A. Grosso, Royal Oak, Mich., assignor to Sylvania Electric Products Inc., a corporation of Delaware

Filed Sept. 3, 1959, Ser. No. 57,416

Term of patent 14 years

(Cl. D61—1)

FIG. 1

FIG. 2

FIG. 3

FIG. 4

Figure 1 is a perspective view of a motion picture camera showing my new design;

Figure 2 is a bottom plan view;

Figure 3 is a left hand side elevation; and

Figure 4 is a rear view.

I claim:

The ornamental design for a motion picture camera, substantially as shown.
